[57] CLAIM

An ornamental design for a nail clipper, as shown and described.

DESCRIPTION

FIG. 1 is a perspective front view of a nail clipper according to my new design, the nail clipper being depicted in a closed (non-operative) state;

FIG. 2 is a perspective front view thereof when in an open (operative) state;

FIG. 3 is a perspective rear view thereof when in a closed state;

FIG. 4 is a perspective rear view thereof when in an open state;

FIG. 5 is a perspective bottom view thereof, its bottom cover being shown in a closed position; and,

FIG. 6 is a perspective bottom view thereof when its bottom cover is in an opened position.

The portions of the opened clipper which cannot be seen in FIGS. 2, 4 and 6 are not being claimed.
